ELECTRIC ARC FURNACE

Kurt Schneider and Hermann Schunck, Bitterfeld, Germany, assignors to I. G. Farbenindustrie Aktiengesellschaft, Frankfort-on-the-Main, Germany

Original application January 23, 1937, Serial No. 121,988. Divided and this application January 11, 1939, Serial No. 250,302. In Germany January 28, 1938

2 Claims. (Cl. 13—11)

This invention relates to a method of and means for magnetically blowing electric arcs on metal electrodes and is a divisional application from our copending application Serial No. 121,988 5 entitled Electric arc furnace and filed January 23, 1937.

When metal electrodes are employed in electric arc furnaces, it is necessary to cause the points where the arc is struck to migrate over the electrodes, in order to prevent them from fusing under the influence of the temperatures generated at the striking point. This migration can be effected by blowing the arc, by means of a current of gas, by mechanically moving, for example rotating, the electrodes or by generating in the proximity of the arc a magnetic field energized by direct or alternating current. In the last-named method however, the generating of said field by means such as electromagnets separated and remote from the electrodes themselves, entails, especially in the case of electric furnaces of the covered type of corresponding modification in the furnace design, in order to accommodate the electromagnets. This imposes limitations on the form 20 of the furnace chamber which are frequently inconvenient or undesirable. On the other hand when the energizing coil is situated outside the shell of the furnace difficulties are encountered in adequately heat-insulating the shell.

30 The present invention aims at obviating the necessity of providing arc-blowing means separate from the electrodes and the disadvantages consequent thereon, by generating the electromagnetic blowing field in the electrode itself by means of an electric current circulating round or passing through the electrode.

This arrangement, in which the means energising the magnetic field form an integral unit with the electrode, does not in any way interfere with the normal furnace design. For example, in the case of shaft furnaces, the shell may be provided with heat-insulating layers of any convenient thickness, or in the case of drum furnaces, which are particularly favored in view of their thermal economy, such furnaces may be equipped with metal electrodes, which was hitherto considered impossible. Gas-reaction furnaces too, can be of particularly simple design, since the reaction chamber can be designed solely with a view to 40 obtaining optimum conditions of flow in the gas space, without having to take into consideration the restrictions otherwise imposed by the accommodation of the electromagnetic blowing means.

55 In order more clearly to understand the inven-

tion, reference is made to the accompanying drawing which illustrates diagrammatically and by way of example an embodiment thereof.

E_1 and E_2 designate electrodes of the well known hair-pin design. B and C denote respectively the in- and out-leads for the working current which generates the arc L between the electrodes E_1 and E_2 , the path of the current being therefore from B to C via L . Arranged adjacent the open end of each electrode is a transformer W . The primary 5 of said transformer P is provided by lead B , said lead being connected to electrode E_2 at D . The secondary of the transformer is designated by S , the secondary being connected to electrode E_2 at D_1 and F . It will be seen from this arrangement 10 that the applied voltage forces the working current directly through the primary P to the electrode E_2 . The working current in passing through the primary induces in the secondary S an auxiliary current of high strength and very 15 low voltage. Said induced current generates the magnetic field, the lines of force of which are represented by the arrows K on the drawing, said lines of force surrounding the elements, even 20 at the striking points thereof.

In the event that the source of current supply is direct current, the auxiliary current may be generated by a thermo-element.

If different types of current be employed for the working and energising currents, i. e. direct 30 current as working current and alternating current as energising current or vice versa, the arc will not be extinguished but will travel to and fro on the electrode, the resulting arc being thus evenly distributed on both sides of the electrode. 35 On the other hand, if direct current, or alternating current, be exclusively employed, the arc will assume the form of a stationary semi-circular disc. In such case the current energising the electromagnetic field can be generated, in a particularly simple manner as shown in the drawing, in a transformer energised by the working current, and, if alternating current be employed, the correct phase relation between the working current and the energising current is automatically obtained.

When heating solid or liquid substances disposed on the hearth of the furnace, for instance when applying the invention to a horizontal drum furnace, and when the electrodes are arranged 50 horizontally and either only direct, or only alternating, current is used, the semi-circular arc may be directed downwards and may be caused to play directly on the charge material, whilst the ceiling 55 of the furnace is thus protected. In such case,

when the charge to be melted is a conductor, the arc is struck not only between the two electrodes, but also between each electrode and the conducting charge material, whereby a particularly favorable utilisation of energy is assured.

5 In order to avoid extinction of the arc when operating solely with alternating current, alternating currents of different frequencies can be employed for the working current and for the energising current, provided that both frequencies are in integral proportion and that they have a series of zero points in common.

We claim:

1. An electric arc furnace comprising two electrodes, at least one of such electrodes being of hair-pin design, means for supplying a working current through and across the gap between said

electrodes, a primary coil in the path of said working current and adjacent to said electrode of hair-pin design, a secondary coil inductively coupled with said primary coil and connected with the ends of said electrode of hair-pin design, 5 said primary and said secondary being so dimensioned and arranged that the working current generates a current of high intensity and low voltage which is superimposed on the working current, traverses only said electrode of hair-pin 10 design, and generates a field consisting of a series of circular lines of force closely surrounding said hair-pin electrode along its length.

2. An electrical arc furnace as defined in claim 1 wherein both elements are of hair-pin design. 15
